UNITED STATES PATENT OFFICE.

LOUIS C. CONNOR, OF KANSAS CITY, MISSOURI.

DESIGN FOR A CASE FOR TIMEPIECES.

45,902.

Specification for Design.

Patented June 9, 1914.

Application filed November 22, 1913. Serial No. 802,555. Term of patent 3½ years.

To all whom it may concern:

Be it known that I, LOUIS C. CONNOR, a citizen of the United States, residing at Kansas City, Jackson county, State of Missouri, have invented a new, original, and ornamental Design for a Case for a Time-piece, of which the following is a specification, reference being had to the accompanying drawing, forming a part thereof.

The figure is a face view of a case for a time piece, showing my new design.

I claim:

The ornamental design for a case for a time piece, as shown.

In testimony whereof I affix my signature in the presence of two witnesses.

LOUIS C. CONNOR.
